ADJUSTABLE SPRING CLAMP

Fred R. Dorner, Middletown, Ohio

Application March 23, 1949, Serial No. 82,965

5 Claims. (Cl. 24—250)

1

This invention relates to an adjustable spring clamp or clasp, and more particularly to a clasp embodying two gripping jaws formed of sheet material.

It is the object of the present invention to provide a rugged clamp of sheet metal composed of but few parts and which may be fabricated economically.

It is a further object of the invention to provide a clasp composed of two relatively movable jaws which are capable of a wide range of separation therebetween, and a camming member for resiliently pressing one of said jaws towards the other in a manner to secure a tight clamping of the material between the jaws at all positions of separation therebetween.

It is a further object of the invention to combine two relatively movable jaws with a camming pressing member in such a manner that the resulting clamp remains effective over a long period of time without wear or deterioration of the parts or reduction in the effective clamping action between the jaws.

It is a further object of the invention to provide a clamp which couples the cam actuator with the movable jaw in order to provide a convenient handle for the latter as the same is moved to its varying positions and until such time as the cam becomes effective to exert its clamping action.

The invention proceeds upon the principle of providing a clamp formed of a base jaw and movable jaw pivoted thereto by means of a reentrant portion on the latter terminating in lateral extensions which act as trunnions rotatable in circular openings formed in upstanding wings at the rear portion of the base jaw. The trunnions are operative along a chordal section of the circular or cylindrical portions of the wings, which merge into the main portion of the movable jaw which is adapted to be flexed into pressing engagement against the material disposed between the jaws by the operation of a camming member trunnioned in the upper portion of the circular openings in the above-mentioned wings. These camming trunnions are of greater width than thickness so that as said camming member is rocked approximately 90° to lock the clamp, the greater dimensions of the width act upon the main surface of the movable jaw to firstly fix the trunnions of the movable jaw within the circular bearings in the wings and thereafter press the latter towards the trunnions in the direction of the base jaw to effect a tight clamping of the material adapted to be disposed between the jaws.

1

2

As an additional refinement, the cam actuator is provided with a spring member adapted to releasably engage the rear extremity of the movable jaw so that the latter is moved with the camming member for all free movements of these parts and until such time as the camming member is swung to exercise its camming and clamping action.

Other objects and purposes will appear from the detailed description of the invention following hereinafter, taken in conjunction with the accompanying drawing, wherein

Fig. 1 is a perspective view of the clamp assembly operative on a stack of sheets;

Fig. 2 is a plan view of the clamp;

Fig. 3 is a front elevation of the clamp in released position with parts thereof shown in dotted lines to indicate the free movement of the movable clamp and the cam actuator;

Fig. 4 is a front elevation of the clamp in its effective clamping position;

Fig. 5 is an exploded view in perspective of the three constituent elements of the clamp assembly;

Fig. 6 is a front elevation of a second embodiment of the invention presenting an additional refinement for facilitating the movement of the upper jaw by the cam actuator; and

Fig. 7 is a perspective view of the cam actuator shown in Fig. 6.

In the drawings, the clamp in accordance with the present invention is formed of two relatively movable jaws comprising a base member 10 adapted to have upstanding wings 11 at the rear portion thereof which may be stamped and bent from the plane of the member 10, and a movable spring jaw 15. Circular openings 12 are formed in the upstanding wings 10 which provide bearings for the pivot members of the movable jaw and camming elements as described below.

The movable jaw 15 is formed of spring metal having a downwardly bowed portion 19 at the front thereof and a reentrant portion at the rear which is turned at point 16 and terminates at edge 17. The main portion of the movable jaw 15 is accommodated between the upstanding wings 11 while the downturned extremity thereof at edge 17 is provided with lateral extensions 18 which are adapted to engage within the openings 12 and act as trunnions for the rotary movement of the movable jaw 15 relative to the base 10. These extensions 18 are smaller than the diameter of the openings 12 and are disposed upon a chordal line of each opening and may vary from a horizontal line as shown in Fig. 3 to a

nearly vertical line as the movable jaw is swung upwardly to accommodate different thicknesses of material P adapted to be clamped between the jaws.

The movable jaw 15, possessing inherent resiliency, is adapted to be pressed into tight engagement with the material disposed between the jaws by the manipulations of a camming member 22 provided with a transverse pressing bar 20 having lateral extensions 21 fitting within the upper portions of the openings 12 above the level of the movable jaw 15. The extensions 21 are of greater width than thickness, so that when such extensions are disposed as shown in Fig. 3, the movable jaw is freely movable to any position, which is permitted by the movement of the trunnion extensions 18 and cam extensions 21 there-in. For any predetermined spacing between the jaws, as determined by the thickness of the material therebetween, a turning movement of the camming member 22 in a clockwise direction for approximately 90° effects a turning of the extensions 21 from the position shown in Fig. 3 to that shown in Fig. 4 to resiliently press movable jaw 15 towards the base 10, which serves first to fix the trunnions 18 in their set position and there-after to press downwardly on movable jaw 15 towards the trunnions 18 and tip 19 towards the base 10, to clamp the material P tightly there-between. The effective force on the camming extensions 21 is increased by the moment arm afforded by the offset between the plane of the actuator 22 and the plane of the cam extensions 21 as well as by the length of the former.

Disengagement of the material between the jaws of the clamp may be effected quickly by a turning of the cam plate 22 from the position shown in Fig. 4 to that shown in Fig. 3.

In the modified embodiment of the invention shown in Figs. 6 and 7, the cam actuator plate 32 extends directly from the transverse cam bar 39 with the cam extensions 31. These extensions 31 are of less thickness than width in order to enable the camming force to be exerted upon the movable jaw 15 as the plate 32 is turned from the position shown in full lines in Fig. 6 to clamping position, indicated in dotted lines, for a pad of material P. A spring retainer 34 mounted on the outside face of cam actuator 32 by means of a rivet 35, and provided with a hook extremity 36 at the free end thereof, serves to releasably couple the cam actuator 32 with the movable jaw 15 by the convexity 36 yeldingly engaging the end 16 of the movable jaw. Thereby the movement of the jaw 15 may be effected by the turning movements of the cam plate 32 between its limiting positions when the free end of the jaw 15 is in contact with the base 10 to the maximum raised position of the movable jaw at nearly right angles to the plane of the base 10. Thus, the cam actuator may be moved from the position shown in full lines in Fig. 6 to engage the material P and thereafter upon blocking of the movement of the movable jaw by the presence of the material P therebetween and jaw 10, the actuator plate 32 continues its rotary movement in a clockwise direction with the disengagement of the hook retainer 36 from the curved end 16 in order to permit the cam extensions 31 to come into play within the upper portions of the bearing openings 12 to exert the pressing action on the movable jaw 15 as explained above in conjunction with the first embodiment of the invention. This constructional expedient facilitates the movement of the jaw 15 which is effected through the

intermediary of the cam plate 32 until the latter begins to exert its camming action.

As shown in Fig. 5, the component parts of the clamp are of simple design which may be stamped out easily and shaped as shown at minimum cost. The assembly of the parts may be effected by springing them into place.

While I have described my invention as embodied in a specific form and as operating in a specific manner for purposes of illustration, it should be understood that I do not limit my invention thereto, since various modifications will suggest themselves to those skilled in the art without departing from the spirit of my invention, the scope of which is set forth in the annexed claims.

I claim:

1. A clasp comprising a base member having a gripping portion at the forward part thereof and a pair of upstanding wings on the lateral sides of the rear part thereof provided with aligned circular bearings, a movable jaw cooperating with said base member formed of a reentrantly shaped rear portion and a downwardly extending forward portion adapted to cooperate with the gripping portion of said base, the main portion of said movable jaw being narrower than the spacing between said wings with the downwardly turned rear end portion provided with lateral extensions fitting within said circular bearings, and a camming member provided with lateral extensions pivotally mounted within said circular bearings within the upper portions thereof and above the upper surface of said movable jaw to effect a clamping movement of said movable jaw in one direction of rotation of said camming member.

2. A clasp comprising a base member having a gripping portion at the forward part thereof and a pair of upstanding wings on the lateral sides of the rear part thereof provided with aligned circular bearings, a movable jaw cooperating with said base member formed of a reentrantly shaped rear portion and a downwardly extending forward portion adapted to cooperate with the gripping portion of said base, the main portion of said movable jaw being narrower than the spacing between said wings with the downwardly turned rear end portion provided with lateral extensions fitting within said circular bearings, and a camming member provided with lateral extensions pivotally mounted within and circular bearings within the upper portions thereof and above the upper surface of said movable jaw, said extensions being of a greater width than thickness so that as said cam is rotated from a position in which said extensions are parallel to the upper face of said movable jaw to a position transverse thereto, said movable jaw is urged into clamping engagement with said base member.

3. A clasp comprising a base member having a gripping portion at the forward part thereof and a pair of upstanding wings on the lateral sides of the rear part thereof provided with aligned circular bearings, a movable jaw cooperating with said base member formed of a reentrantly shaped rear portion and downwardly extending forward portion adapted to cooperate with the gripping portion of said base, the main portion of said movable jaw being narrower than the spacing between said wings with the downwardly turned rear end portion provided with lateral extensions fitting within said circular bearings along a chordal line therein, and a cam-

ming member provided with lateral extensions pivotally mounted within said circular bearings within the upper chordal portions thereof and above the upper surface of said movable jaw, said extensions being of a greater width than thickness so that as said cam is rotated from a position in which said extensions are parallel to the upper face of said movable jaw to a position transverse thereto, said movable jaw is urged into clamping engagement with said base member.

4. A sheet metal clasp comprising a base member having a gripping portion at the forward part thereof and a pair of upstanding wings on the lateral sides of the rear part thereof provided with aligned circular bearings, a movable jaw cooperating with said base member formed of a reentrantly shaped rear portion and a bowed forward portion adapted to cooperate with the gripping portion of said base, the main portion of said movable jaw being narrower than the spacing between said wings with the downwardly turned end portion provided with lateral extensions fitting within circular bearings along a chordal line therein, and a camming member formed of an operating plate and a pressing bar normal thereto provided with lateral extensions pivotally mounted within said circular bearings within the upper chordal portions thereof and above the upper surface of said movable jaw, said extensions being of a greater width than thickness so that as said cam is rotated from a position in which said extensions are parallel to the upper face of said movable jaw to a position transverse thereto, said movable jaw is urged into clamping engagement with said base member.

5. A clasp comprising a base member having a gripping portion at the forward part thereof

and a pair of upstanding wings on the lateral sides of the rear part thereof provided with aligned circular bearings, a movable jaw cooperating with said base member formed of a reentrantly shaped rear portion and a bowed forward portion adapted to cooperate with the gripping portion of said base, the main portion of said movable jaw being narrower than the spacing between said wings with the downwardly turned end portion provided with lateral extensions fitting within circular bearings along a chordal line therein, a camming member formed of an operating plate and a pressing bar normal thereto provided with lateral extensions pivotally mounted within said circular bearings within the upper chordal portions thereof and above the upper surface of said movable jaw, said extensions being of a greater width than thickness so that as said cam is rotated from a position in which said extensions are parallel to the upper face of said movable jaw to a position transverse thereto, said movable jaw is urged into clamping engagement with said base member, and a yielding spring member having one end thereof fixed to the back of said cam operating plate and the opposite end hooked into releasable engagement with the rearmost portion of said movable jaw.
